 Woodin, Jr., Pasadena, Calif.

Application April 16, 1943, Serial No. 483,351

4 Claims. (Cl. 179—171)

My invention relates broadly to electron tube circuits and more particularly to a balanced pentagrid tube circuit.

One of the objects of my invention is to provide a circuit arrangement for a pentagrid tube circuit in which a high degree of precision balance may be maintained in the electrical circuits for securing large magnification of feeble electrical currents.

Another object of my invention is to provide a circuit arrangement for a pentagrid electron tube including a cathode, a space charge grid, a balancing grid, a screen grid, a control grid and an anode in which changes in emission current can be balanced or compensated independently of the balancing of other parts of the circuit.

Still another object of my invention is to provide a pentagrid tube circuit in which an adjustable balancing circuit is connected with the space charge grid and cathode for compensating or balancing the circuit against changes in emission independently of balancing arrangements associated with other portions of the pentagrid circuit.

A further object of my invention is to provide a balancing circuit arrangement for a pentagrid tube which includes a cathode, a space charge grid, a balancing grid, a screen grid, a control grid and an anode wherein connection is arranged for the space charge grid to a point intermediate a pair of adjustable resistors disposed in the input circuit to the tube where the resistors are so proportioned that the sum of the resistances and the ratio of the resistances may both be varied in such a way that if positive regulation occurs the opposite condition will produce negative regulation whereby adjustment may be made of the value of the resistors to an intermediate condition of zero regulation.

Other and further objects of my invention reside in the arrangement of a resistance network in the input circuit to a pentode and a tap connection therefrom to the space charge grid of the pentode as set forth more fully in the specification hereinafter following by reference to the accompanying drawing in which:

Figure 1 diagrammatically illustrates one arrangement of balanced pentagrid tube circuit embodying my invention; and Fig. 2 illustrates a modified arrangement of pentagrid tube circuit embodying my invention.

My invention is directed to a balanced pentagrid tube circuit having a high degree of stability independently of variations in voltage supplies to the circuits of the pentode and more particularly independent of electron emission changes in the pentode. I have successfully obtained voltage amplifications of approximately 200 employing the balanced pentagrid tube circuit of my invention. The particular feature of the circuit of my invention is that changes in electron emission are

balanced separately from the balancing of changes in the direct current power supply.

Referring to the drawing in more detail, the pentode is designated at 10 including cathode 11 which is heated by heater element 12, space charge grid 13, balancing grid 14, screen grid 15 serving as a shield for control grid 16 and anode 17. The input circuit to the pentode has been indicated generally at 18 while the output circuit is shown generally at 19. For purposes of determining the condition of ballast, a galvanometer 20 is arranged in the output circuit. It will be understood that connections may extend parallel from the output system of the pentagrid to another tube circuit or other current utilization circuit. The input circuit to the pentode is completed through adjustable resistors R1 and R2 leading to the cathode 11. At a point intermediate resistors R1 and R2 shown at 21, a tapped connection is taken to the space charge grid 13. Resistors R1 and R2 may be varied for changing the resistance value on either side of the connection to the space charge grid for compensating for variations in electron emission from cathode 11.

The power supply to the heater 12 extends from circuit 22 which includes series connected adjustable resistor R8 for controlling the temperature of heater element 12. The direct current power supply for the circuits of the pentode is represented generally at 23 connected between the cathode end of the pentagrid tube circuit at 24 and the anode end of the pentagrid tube circuit at 25. Adjustable resistor R9 is arranged in series between the direct current power supply 23 and the anode circuit of the pentode for approximately regulating the power supplied to the pentode. A potentiometer circuit is connected in parallel with the direct current power supply 23 and regulating resistor R9 across points 26—25 of the circuit as shown. The potentiometer circuit includes series connected individually adjustable resistors R3, R4, R5 and R6. A tap connection 27 between adjustable resistors R3 and R4 in the circuit of Fig. 1 leads to screen grid 15. A tap connection 28 between adjustable resistors R4 and R5 leads to the balancing grid 14. The tapped connection 29 between adjustable resistors R5 and R6 leads through galvanometer 20 to anode 17. The balancing circuit is connected to ground as represented at 30 in both Figs. 1 and 2.

In the arrangement shown in Fig. 1, the balancing of the pentagrid circuit is effected by means of control of potential on screen grid 15 which serves as a shield for control grid 16. In the arrangement shown in Fig. 2, the balancing of the pentagrid circuit is effected by controlling the potential on balancing grid 14. In both arrangements the compensation for changes in electron emission is performed independently of

the balancing of the pentagrid tube circuit as a whole.

The compensation for variations in electron emission is effected by adjustment of the resistance values of adjustable resistors R1 and R2. The balance for variations in electron emission depends upon both the total resistance $R1+R2$ and the ratio of these two resistances both being varied in such a way that if positive regulation occurs the opposite condition will produce negative regulation. Resistors R1 and R2 are independently varied until it is determined under what condition negative regulation occurs. Then, noting both conditions of positive regulation and negative regulation, the value of the total resistance $R1+R2$ and a ratio of $R1/R2$ is selected such that zero regulation is obtained.

In practice the manner of balancing for emission is to change R1 until a balancing condition is obtained with a given galvanometer deflection on galvanometer 20. Then resistor R2 is changed to bring the galvanometer deflection back to zero. This process is repeated a series of times until a balancing condition is obtained at zero reading of the galvanometer 20. This is really balancing for constant plate current with change of emission from the cathode which is approximately the desired balance required.

For balancing changes in the D. C. supply, resistor R4 is varied until some balanced condition occurs with a given deflection in the galvanometer 20 and then by changing resistor R7 to bring the galvanometer deflection back to zero and repeating this operation until a balance of zero deflection of the galvanometer is obtained. If the potential between the anode 17 and the junction 29 between resistors R5 and R6 goes negative (indicated by the direction of the current through the galvanometer 20) when the D. C. supply voltage increases then the potential of the screen grid 15 must be increased to counteract this and vice versa when this potential goes positive. If necessary, resistors R3, R5 and R6 can be changed and the whole process repeated until satisfactory balance is obtained. The galvanometer 20 can be balanced against either a tap on the divider or a constant voltage with respect to ground.

I have found the balancing system of my invention highly efficient in operation and have obtained voltage amplifications of approximately 200 using the circuit of my invention. I have found the independent circuit for compensating for electron emission highly efficient in pentagrid circuits which are subject to fluctuations in heater potential and variations in the direct current power supply. Such variations are extremely difficult to overcome and with the wider use of radio circuits in mobile units, are inherent where the voltage supplied to the radio circuits is often dependent upon an over-charging condition of a generator due to speed of the mobile unit. This is true independently of the fact that storage battery may normally be floated across such power supply lines as persistent over-charging from the generator often has detrimental effects upon the circuits of the pentagrid tubes. Such variations, however, have but small effect upon the efficient operation of the pentagrid tube circuit of my invention.

It is understood that having once determined the proper resistance values between adjustments hereinbefore explained, resistances of fixed values may be substituted in the pentagrid tube circuits to meet an average condition of

the variations which are to be expected in any given power supply system.

While I have described my invention in certain of its preferred embodiments, I realize that modifications may be made and no limitations upon my invention are intended other than may be imposed by the scope of the appended claims.

What I claim as new and desire to secure by Letters Patent of the United States is as follows:

- 10 1. A balanced electron tube system comprising a pentagrid electron tube having electrodes including a cathode, a heater element for said cathode subject to fluctuating heater supply current, a space charge grid, a balancing grid, a screen grid, a control grid and an anode, a direct current supply source subject to variation in voltage, a plurality of means for impressing selected potentials on said electrodes from said supply source, an output circuit connected with said anode, an input circuit connected with said control grid and said cathode, an auxiliary circuit comprising a pair of independently adjustable resistors arranged in said input circuit, and a tap intermediate said resistors electrically connected with said space charge grid.
- 15 2. An electron tube circuit including a multi-grid tube including a cathode, a space charge grid, a control grid and an anode, an input circuit including said control grid and a circuit path to said cathode, a pair of separately adjustable resistors included in said path, a tap intermediate said separately adjustable resistors, a connection from said tap to said space charge grid, and an output circuit connected with said anode.
- 20 3. A balanced electron tube system comprising a pentagrid electron tube having electrodes including a cathode, a heater element for said cathode subject to fluctuating heater supply current, a space charge grid, a balancing grid, a screen grid, a control grid and an anode, a direct current supply source subject to variation in voltage, a plurality of means for impressing selected potentials to said electrodes from said supply source, an output circuit connected with said anode, an input circuit connected with said control grid and said cathode, means for electrically balancing the circuits leading to said balancing grid, said screen grid and said anode, and independent means disposed in said input circuit comprising a pair of series connected separately adjustable impedances with an intermediate point therebetween connected with said space charge grid and said cathode for compensating for changes in emission from said cathode.
- 25 4. A balanced electron tube system comprising a pentagrid electron tube having electrodes including a cathode, a heater element for said cathode subject to fluctuating heater supply current, a space charge grid, a balancing grid, a screen grid, a control grid and an anode, a direct current supply source subject to variation in voltage, a plurality of means for impressing selected potentials on said electrodes from said supply source, an output circuit connected with said anode, an input circuit connected with said control grid and said cathode, a resistance network, circuit connections including said resistance network in said input circuit, said resistance network including a pair of independently adjustable resistors connected in series and a connection from a point intermediate said adjustable resistors in said resistance network to said space charge grid for compensating for variations in electron emission from said cathode.
